UNITED STATES PATENT OFFICE

ROY WALTER SWOPE, OF COLUMBUS, GEORGIA, ASSIGNOR TO CENTENNIAL COTTON GIN COMPANY, OF COLUMBUS, GEORGIA, A CORPORATION OF GEORGIA

COTTON PRESS

Application filed October 20, 1927. Serial No. 227,472.

The invention relates to new and useful improvements in cotton presses, and more particularly to a cotton press of the double box type.

6 An object of the invention is to provide a supporting structure for the boxes of the press which is very rigid and which supports the boxes as they revolve about the support.

10 A further object of the invention is to provide a supporting structure for the revolving boxes of a cotton press which permits of an I-beam being used for supporting the boxes, and around which said boxes may be revolved.

15 A further object of the invention is to provide a supporting structure of the above character wherein a supporting bracket is fixed to the I-beam and a supporting plate is connected to and supports the boxes, and has in turn a ball-bearing support on said bracket.

20 These and other objects will in part be obvious and will in part be hereinafter more fully described.

In the drawings which show by way of illustration one embodiment of the invention:

Figure 1 is a side view of a cotton press embodying the improvements.

Fig. 2 is a sectional view on an enlarged scale on the line 2-2 of Fig. 1.

30 Fig. 3 is a sectional view on an enlarged scale through a portion of the supporting bracket and the supporting plate on the line 3-3 of Fig. 1.

Fig. 4 is a bottom plan view of the supporting plate on which the boxes are mounted.

Fig. 5 is a plan view of an upper plate joining the boxes.

The invention is directed to a cotton press of the type wherein double boxes are supported relative to a pressing apparatus, so that they may be positioned alternately for filling and for pressing the baling.

The invention is directed more particularly to the supporting means for the baling boxes, which includes an I-beam which is rigidly attached to the frame of the cotton press. Mounted on this I-beam is a bracket which is firmly clamped to the I-beam at a distance above the base of the frame-work of the cotton press. This bracket is preferably made

in two parts, which are clamped to the I-beam, thus making up a continuous supporting ledge at the upper face of the bracket, which supporting ledge is formed with an annular groove or race-way for balls. This race-way is positioned so that the balls traveling around the race will travel around the center axis of the I-beam. The cotton press includes two boxes. These two boxes are mounted on suitable supporting beams which are attached to a plate having a central opening therethrough of a diameter equal to the greatest diameter of the I-beam, so that the I-beam may pass through the opening and the plate freely revolve about the I-beam.

On the lower face of this plate is an annular groove or ball race, which is positioned directly above the ball race on the bracket, and a series of balls run in the races. This serves as the sole support for the boxes. The two boxes are joined at a point well above the supporting bracket by a plate which has an opening therethrough for the I-beam to pass, so that the I-beam is free from this plate.

Referring more in detail to the drawings, the cotton press is shown as including a supporting base 1 having a frame including columns 2, and an upper frame member 3a mounted on the columns. Also mounted in the base and rigidly carried thereby is an I-beam 3. This I-beam is likewise bolted at 4 to the upper member 3a of the frame. The I-beam joins the base and the upper member and serves as a supporting means for the inner end of the upper member 3a.

Mounted on this I-beam as a support are two baling boxes 5 and 6. These baling boxes are joined by cross beams 7 near the bottom of the boxes, and also by cross beams 8. The cross beams are bolted to a supporting plate 9. This supporting plate is shown in bottom plan view in Fig. 4. Said plate includes a central opening 10 which is of a diameter so that the I-beam may extend through the opening and be free from contact with the plate. This plate 9 is also provided with an annular groove or race-way 11, which is formed about the same center as the inner opening 10. The plate 9 extends laterally from the central opening and the cross beams 7 are bolted to

this plate, there being one for each end of the plate. The bolts for securing the cross beams to the plate 8 pass through openings 11'. The beams 9 are angle iron beams, so that the vertical flange thereof may be bolted to the boxes, while the horizontal flange is bolted to the plate 9.

Fixed to the I-beam 3 is a bracket 12. This bracket 12 is made in two sections, as shown in Fig. 2 and bolted together by suitable bolts 13. The two sections of the bracket 12 when bolted together are firmly clamped and secured to the I-beam. The bolts 13, as clearly shown in Fig. 2, pass through the central web of the I-beam. In the upper face of the bracket there is an annular groove or ball race 14. This annular groove is centered about the center axis of the I-beam, and it is directly opposed to the annular groove or ball race 11 in the lower face of the plate 9. The balls 15 are placed in this ball race of the bracket and serve as a ball bearing support for the plate 9 which carries the boxes. The ball bearing support entirely surrounds the I-beam and is at all points a sufficient distance out from the center of the I-beam so as to carry the load, although it is unequally distributed, as in the operation of the press one box is loaded and then moved to a position for pressing, while the box which is being emptied at the pressing station is returned to the loading station.

There is a plate 16 shown in detail in Fig. 5 which is secured by suitable bolts 17 to each box structure. This plate 16 has an opening 18 therethrough which is of sufficient diameter to surround the I-beam. Any tilting of the boxes on the ball bearing support will be prevented by this plate through its engagement with the I-beam, although normally the supporting structure is sufficient to carry the boxes with little or no tilting. This uneven load referred to above will, however, produce more or less of a lateral strain on the support for the boxes. The I-beam makes a very rigid, durable and efficient supporting means on which the boxes may revolve. Each box is provided with the swinging doors and with suitable retaining devices of the usual construction. The cotton press also includes a ram 19 which engages a movable bottom 20 in the box, when it is brought over the ram, and forces the bottom up in the box, and thus it is that the cotton is carried into the baling portion at the upper end of the box and firmly compressed therein against the members 21 carried by the upper frame of the press. The manner of filling the boxes and pressing the cotton therein and removing the bale from the box is very common, and further description thereof is not thought necessary.

It is obvious that minor changes in the details of construction and the arrangement of parts may be made without departing from

the spirit of the invention as set forth in the appended claim.

What is claimed as new is:

In a cotton press the combination of a supporting frame including a base and an upper member, an I-beam rigidly connected to the base and said upper member, a plurality of pressing boxes and means for supporting said pressing boxes on said I-beam whereby said boxes may be revolved about said I-beam from filling to pressing positions, said supporting means including a supporting bracket clamped to the I-beam at a point above the base, said supporting bracket having an annular semi-circular ball race in the upper face thereof spaced from the outer edge of the I-beam, a plate rigidly attached to the boxes and having an opening through which the I-beam passes, said opening being shaped so as to permit the plate to revolve freely about the I-beam, said plate on its under face having an annular semi-circular ball race spaced from the edge of said opening and directly above the ball race in the supporting bracket, balls running in said ball races, and a second plate attached to the boxes at a point well above the bracket and having a circular opening through which the I-beam passes, said opening being shaped so that the plate is entirely free from contact with the I-beam.

In testimony whereof, I affix my signature.

ROY WALTER SWOPE.
